SICKLE GRINDER

Otto P. Rehse, Orland, Calif.

Application January 11, 1952, Serial No. 265,933

2 Claims. (Cl. 51—33)

1

This invention relates generally to grinders, and more specifically to a swing grinder for sickle blades.

The primary object of this invention is to provide a swing grinder for sickle blades in which the grinding wheel may be reciprocated transversely of the sickle blade in a horizontal plane.

Another object of this invention is to provide a swing grinder for sickle blades having support means for the sickle blade to which the sickle blade may be quickly clamped.

Another object of this invention is to provide a swing grinder for sickle blades having a support for the sickle blade which needs no adjustment other than the clamping of the blade in place.

Another object of this invention is to provide a swing grinder in which the grinding wheel and its drive means are mounted on a support frame in counter-balanced relation.

Another object of this invention is to provide a swing grinder which is a compact unit and of simple construction whereby it may be economically manufactured.

A further object of this invention is to provide a swing grinder for sickle blades which is simple and easy to operate through numerous different angles with a minimum of fatigue for the operator.

With these objects definitely in view, this invention resides in certain novel features of construction, in combination and arrangement of elements and portions as will be hereinafter described in detail in the specification, particularly pointed out in the appended claims, and illustrated in the accompanying drawings which form a material part of this application, and in which:

Figure 1 is a top plan view of the swing grinder which is the subject of this invention;

Figure 2 is a partial front elevational view of the swing grinder of Figure 1, the legs of the support having their lower ends cut off;

Figure 3 is an end elevational view of the swing grinder of Figure 1 and shows in dotted lines a second position of the grinding wheel and its associated means; and

Figure 4 is an enlarged partial transverse vertical sectional view of the swing grinder and shows in more detail the grinding wheel and its associated support means, the grinding wheel being shown in its grinding position by dotted lines.

Similar characters of reference designate similar or identical elements and portions throughout the specification and throughout the different views of the drawings.

2

Referring now to the drawings in detail, this invention includes a support 10, a track way structure 12 and a grinding wheel supporting means 14. Referring now to Figures 1 and 2 in particular, it will be seen that the support 10 includes rectilinearly spaced legs 16 having the shape of an A-frame. The legs 16 are arranged in pairs at each end of the support 10, and the cross arms 18 extending between and secured to the apex of each pair of legs. Secured to the upper surface of the cross arms 18 in spaced parallel relation are a pair of longitudinally extending frame members 20 which lie in a horizontal plane. Extending between and secured to the ends of the longitudinally extending frame members 20 are end cross frame members 22. An intermediate cross frame member 24 extend between and is secured to the longitudinally extending frame members 20 intermediate their ends. The cross frame members 22 and 24 are preferably tubular and circular in cross section, and are secured to the longitudinally extending frame rails 26 by bolts 28 which pass through the longitudinally extending frame members and the cross frame members. The longitudinally extending frame members are preferably angle shaped in cross section and have horizontal and vertical flanges. Mounted on the upper end of the vertical flange of one of the longitudinally extending frame rails 26 is a longitudinally extending sickle blade support 28 in the form of an angle bar having flanges of equal width, and the flanges lying at a 45° angle to the horizontal, the apex being secured to the vertical flange of the longitudinally extending frame member 20. A sickle bar 30 may be clamped to the support 28 in a horizontal plane by a conventional C-clamp 32 having an adjusting screw 34.

The track way 12 is mounted on the end cross frame members 22 for sliding movement longitudinally thereof and in transverse relation to the support 10. The track way 12 includes a pair of vertical standards 36, which are rigidly secured to the sleeves 38 by welding or other equivalent fastening means. The sleeves 38 are mounted over the circular cross sectional end cross frame members 22 for sliding motion longitudinally thereof. The sleeves 38 are locked against relative motion with respect to the end cross frame members 22 by locked screws 40. Braces 42 are provided between the sleeves 38 and the vertical standards 36. At the upper ends of the standards 36 are track receiving brackets 44 having an axis perpendicular to the center line of the standards 36 parallel to the longitu-

dinarily extending frame rails 20. A longitudinally extending circular cross sectional rail 46 extends between and is secured to the brackets 44 by lock screws 48. In view of the foregoing, it is readily apparent that by releasing the lock screws 40, that the track 46 may be shifted toward or away from the sickle bar 30 in its clamped position, and at the same time remaining parallel thereto.

Carried by the track 46 for movement longitudinally thereof is the grinding wheel structure 14. The grinding wheel structure 14 includes a carrier and a grinding wheel supporting frame. The carrier consists of a plate 50 which has mounted on one side thereof a pair of spaced rollers 52. The rollers 52 are rotatably mounted on bolts 54 secured to the plate 50. Secured to the plate 50 in overlapping relation is an arm 56. The arm 56 is carried at the lower end of the plate 50 and extends downwardly therefrom in a vertical plane. The arm 56 has integral with its upper end a longitudinally extending flange 58 which is normal to the plane of the plate 50. Carried by the longitudinally extending flange 58 is a longitudinally extending guide 60 which has a U-shaped cross section and opens outwardly. Referring to Figure 4 in particular, it will be seen that the U-shaped guide 60 in cooperation with the rollers 52 form a pair of spaced, substantially circular journals whereby the plate 50 and its associated arm 56 may be pivoted about the rail 46. Secured to the lower end of the arm 56 is a bracket 62 having a longitudinally extending body portion 64, a vertically extending flange 66 secured to the arm 56 by bolt means 68, and a pair of downwardly extending spaced flanges 70. The aforesaid grinding wheel supporting frame is pivotally mounted between the downwardly extending flanges 70.

Referring now to Figure 1, it will be seen that the grinding wheels supporting frame includes a pair of transversely extending side rails 72 and a plurality of cross frame members in the form of supports. The cross frame members include a pair of spaced bars 80 extending between the side rails 72 and secured thereto adjacent one end. The support bars 80 carry an electric motor 78 which is secured thereto by a plurality of bolts 76. Extending between and secured to the other end of the side rails 72 is a handle 74. The handle 74 is preferably tubular and secured to the side rails 72 by a bolt extending through the side rails 72 and the handle 74. The bolt being generally designated by the numeral 82. Rotatably journaled on the side rails 72 adjacent the handle 74 is a shaft 84 on which is mounted a grinding wheel 86. When the grinder is used to sharpen a sickle bar, the grinding wheel 86 is of the conventional double bevel type. Carried by the side rails 72 adjacent the grinding wheel 86 and away from the handle 74 is a guard 88. The guard 88 is pivotally mounted between the side rails 72 by a bolt 90, and overlies the grinding wheel 86. The grinder wheel supporting frame is pivotally secured to the brackets 62 by bolts 92 passing through the downwardly directed flanges 70 of the bracket and the side rails 72 of the supporting frame.

The grinder wheel 86 is mounted on the shaft 84 in centered relation by the use of spacers 94. Mounted on one end of the shaft 84 externally of the side rails 72 is a driven pulley 96. Mounted on the shaft 98 of the electric motor 78 is a drive pulley 100 which is connected to the driven pulley 96 by a drive belt 102. The electric motor

78 is connected to any convenient power source by the wire 103. As is clearly shown in Figure 1, the cutting edges 104 of the sickle bar 30 are at an angle to each other to form a triangular opening therebetween. It is readily apparent that when the grinder wheel 86 is brought into engagement with the cutting edges 104 and moved transversely of the sickle bar, the two intersecting cutting edges are sharpened at the same time.

Referring now more specifically to Figure 4, it will be seen that since the carrier is pivotally mounted on the track 46 and the grinder wheel supporting frame is pivotally carried by the carrier, that the grinder wheel 86 may easily follow the cutting edge 104 of the sickle bar 30 even if the sickle bar deviates slightly from the horizontal. Due to the ability of the grinding wheel 86 to be moved along any desired line transversely of the support 10, the sickle bar 30 may be quickly clamped to the sickle bar support 28 by the C-clamp 32 without requiring complicated adjustments. However, in order that the sickle bar 30 may be clamped in the same position each time it is ground, the sickle bar support 28 is provided on its upper surface adjacent its right hand end, as viewed in Figures 1 and 2, with an angle shaped stop member 106.

In view of the foregoing, it is readily apparent that the swing grinder which is the subject in this invention, is for metal stock such as a pipe, angle bars, flat stock, etc., which may be readily attained. Furthermore, the construction of this swing grinder is extremely simple and may be formed in any metal working shop. Also, due to the counter-balanced supporting of the grinder wheel supporting frame, the grinder may be used with very little effort on the part of the operator.

Although the grinder has been illustrated and described as being supported by the legs 16 and the cross arms 18, it is not intended to so limit the invention as the grinder may be equally as well supported by other means.

The operation of this machine will be understood from the foregoing description of the mechanical details, thereof, taken in combination with the above mentioned objects and the drawings. Further description would appear to be unnecessary.

Minor modification of the machine, varying in minor details from the embodiment of the machine illustrated and described here, may be resorted to without departure from the spirit and scope of the invention, as defined in the appended claims.

Having described the invention, what is claimed as new is:

1. A swing grinder comprising a support, spaced standards mounted on said support, a track extending between and secured to the upper ends of said standards, a grinding wheel, grinding wheel mounting means mounted on said track for sliding longitudinally thereof, said mounting means including pivot means whereby said grinding wheel may be reciprocated transversely of said track in a horizontal plane, said standards being movable transversely of said support.

2. A swing grinder comprising a support, spaced standards mounted on said support, a track extending between and secured to the upper ends of said standards, a grinding wheel, grinding wheel mounting means mounted on said track for sliding longitudinally thereof, said mounting means including pivot means whereby said grinding wheel may be reciprocated transversely of

said track in a horizontal plane, said standards being movable transversely of said support, a sickle bar support carried by said support in parallel relation to said track, clamp means carried by said sickle bar support for clamping a sickle bar on said sickle bar support in a horizontal plane, said sickle bar support forming a portion of a support for said standards.
